GARMENT STORAGE RACK

William F. James, Overland Park, Kans., assignor to Equipment Manufacturing Company, Inc., Kansas City,
Mo., a corporation of Missouri

Filed Nov. 4, 1968, Ser. No. 14,289

Term of patent 14 years

Int. Cl. D6—01

U.S. Cl. D33—8

FIG. 1 is a front perspective view of the garment storage rack;

FIG. 2 is a rear elevational view of the garment storage rack;

FIG. 3 is a side elevational view of the garment storage rack; and

FIG. 4 is a horizontal sectional view thereof taken along line 4—4 of FIG. 3.

I claim:

The ornamental design for a garment storage rack, as shown.
